A. H. DYSON.

TELEPHONE SYSTEM.

APPLICATION FILED JAN. 20, 1902.

923,035.

Patented May 25, 1909.

UNITED STATES PATENT OFFICE.

ALFRED H. DYSON, OF CHICAGO, ILLINOIS, ASSIGNOR TO AMERICAN ELECTRIC TELEPHONE COMPANY, OF CHICAGO, ILLINOIS, A CORPORATION.

TELEPHONE SYSTEM.

No. 923,085.

Specification of Letters Patent. Patented May 25, 1909.

Application filed January 20, 1902. Serial No. 90,383.

To all whom it may concern:

Be it known that I, ALFRED H. DYSON, a citizen of the United States, residing at Chicago, in the county of Cook and State of Illinois, have invented a certain new and useful Improvement in Telephone Systems, of which the following is a specification.

My invention relates to telephone systems in general, but more particularly to telephone systems involving two or more exchanges connected by trunk lines, and especially to the supervisory or clearing out signals by which the operators at the different exchanges are advised that the subscribers are through talking. In telephone systems of this character it is the practice, for example, to connect two exchanges by means of a trunk line, and to in this way make it possible for a subscriber of one exchange to communicate with a subscriber of the other exchange. The operator at the exchange receiving the call is ordinarily termed the "originating operator," while the operator at the other exchange is usually known as the "trunking operator." When a call is sent in to the originating operator, the latter then communicates with the other exchange, stating the number of the subscriber called for. The trunking operator then inserts the plug of the trunk cord circuit in the jack of the called subscriber, and at the same time the originating operator is instructed to insert the plug of the cord circuit in the jack of the trunk line between the two exchanges. In this way the calling subscriber is connected up with the called subscriber, and when the latter answers the call the two sub-stations are then in circuit. It is also the practice to provide the exchanges with clearing out or supervisory signals, so that the operator at each exchange may know when the subscribers have finished their conversation.

In the system to which my invention particularly relates, the hanging up of the receiver by the called subscriber operates to light two supervisory lamps, one at the switchboard of the trunking operator, and the other at the switchboard of the originating operator at the other exchange. In this way both operators are advised that the called subscriber is through talking. The arrangement is also such that when the calling subscriber hangs up the receiver, a supervisory lamp is lighted at the switchboard of

the originating operator, and when the latter withdraws the plug from the jack of the trunk line, a supervisory signal, preferably a lamp, is also operated at the switchboard of the trunking operator. In this way the trunking operator simply acts on the instructions of the originating operator, and makes such connections and disconnections as are called for and signaled by the originating operator.

While, as stated, my invention relates generally to trunking telephone systems, it relates more particularly to the clearing out or supervisory signals for the two exchanges, and especially to the circuit arrangement whereby the originating operator advises the trunking operator that the calling subscriber is through talking and has hung up the receiver.

Generally stated, it is the object of my invention to provide a simple and efficient circuit arrangement for operating and controlling the clearing out signals of a trunk line system of the complete metallic circuit and double supervisory type.

A special object of my invention is to provide an improved trunking cord circuit, consisting preferably of but a single plug and cord.

A further object is to provide local circuits and an improved arrangement of relays for operating the supervisory or clearing out signals at the trunking exchange.

It is also an object of my invention to avoid the use of objectionable grounded circuits between the two exchanges, and to thereby render the supervisory or clearing out signals between the two exchanges more certain in their operation.

A further object of my invention is to provide an improved arrangement of relays and supervisory lamps in the single cord of a trunking cord circuit.

In addition to these, it is also an object of my invention to provide certain details and features of improvement tending to increase the general efficiency, and to render a system of this character more serviceable and reliable in its operation.

To the foregoing and other useful ends, my invention consists in matters hereinafter set forth and claimed.

The accompanying drawing is a diagram showing the usual or ordinary cord circuit

- for the originating operator, the trunking cord circuit for the trunking operator at the other exchange, the two cord circuits being shown connected by the trunk line between the two exchanges, and the apparatus at the called station, together with the substation line and terminal apparatus, being shown connected with the cord circuit of the trunking operator.
- 10 As thus illustrated, the arrangement involves a sub-station having a receiver 1, a receiver hook 2, a bell 3, grounded at 4, and the two contact points 5 and 6. It will be understood, however, that the apparatus thus located at the sub-station can be of any suitable form or character, and that only such parts or instruments are shown as is necessary to an understanding of the invention. The said sub-station is connected 20 by metallic line conductors 7 and 8 with the central station or exchange. As shown in the drawing, this exchange is provided with a multiple switchboard, and with a suitable line or calling signal. The switchboard apparatus involves a conductor 9, forming medium of electrical connection between the ground 10 and the contact 11, the latter being normally in contact with the contact piece 13. Contact pieces 12, 13, 14, 15, 16 and 17 are also provided, the strips or contact pieces 13, 14 and 16 being preferably movable and connected by insulation. The contact piece 16 is adapted to be engaged by the armature 18 of the relay 19, when the latter is energized by the insertion of the trunk cord circuit plug in the jack of the switchboard. The coil of said relay is preferably connected by a conductor 20 with the battery 21, the latter being grounded at 22. 30 From the pole of this battery a conductor 23 leads to the coil of the relay 24, and from this relay the current passes through conductor 25 to the contact piece 17, which is normally in contact with the movable contact piece 16. This relay 24 can be arranged to serve as the calling or line signal for the sub-station having the receiver 1. A conductor 26 connects the relay 19 with the jacks on the switchboard. The conductors 27, 28 and 30 connect certain of the said contact pieces with the said jacks, while the conductor 29 leads from one of said contact pieces through the resistance 31 to the ground at 32. The conductors 33, 34, 35 and 36 serve as medium of electrical connection between the jacks. As illustrated, the upper jack comprises the casing or testing ring contact 37, the sleeve contact 38, and the tip contact 39. The contact piece 40 is connected with the tip contact strip 39 by insulation 41. The contact piece 40 is adapted to engage the contact point 42 when the plug is inserted, completing a circuit from the battery 21 through the relay 19 and the ground 22 and 43. The lower

jack, which is shown in use, the plug of the trunking cord circuit being inserted, comprises the ground 44 and contact 45, and the contact strips or springs 46, 47, 48 and 49. It will be seen that the jacks are similar in form and construction.

The plug which is inserted in the lower jack comprises the tip contact 50 and the sleeve contact 51, connected respectively with the tip and sleeve strands 53 and 52 of the single cord with which the trunking operator is provided at the exchange where the said jacks are located. This single cord comprises the springs 54 and 55 of the ringing key, and the adjacent contacts 56, 57, 58 and 59, it being observed that the said springs are normally in contact with contacts 56 and 58. Conductors 60 and 61 lead respectively from the contact points 57 and 56, while conductors 62 and 64 lead respectively from the contacts 59 and 58. There is also a conductor 63, a spring 65 of the ringing key, and adjacent contact points 66 and 67. The other spring 68 of the ringing key is arranged to coöperate with the contact points 69 and 70. A conductor 71 connects the contact point 70 with the ringing generator 72, which is adapted to ring the bell 3 at the sub-station. The said generator is preferably grounded at 73. The conductors 74 and 75 connect the contact points 67 and 69 with the springs 76 and 77 of the listening key. This listening key can be provided with contact points 78 and 79, the latter connected by a conductor 80 and the coil 81 with the operator's receiver or head telephone 82. The conductor 83 connects this receiver to the contact point 78. The springs 76 and 77 are connected by conductors 84 and 85 with the coils 86 and 87 of the differential relay B. The conductor 80 is preferably provided with a condenser 89, and a contact point. A contact point 88, a conductor 90, and an armature 91 are associated with the said relay B. This armature is preferably normally away from the said contact point and is also preferably grounded at 92. The conductor 93, the repeating coil 94, the battery 95, the repeating coil 96 and the conductor 97 are connected up in series with the coils of said differential relay. The said battery is preferably grounded at 98. The said repeating coils 94 and 96 serve to inductively connect the two parts of the single cord. In the other part of the cord circuit the said repeating coils 94 and 96 are separated by a condenser 99. A conductor 100 connects the repeating coil 96 with the conductor 126 of the trunk line between the two exchanges, while the conductors 101, 103 and the coil of the relay 104 form a bridging connection across this part of the cord circuit. The conductor 102 preferably leads from the conductor 101 to an associated contact piece. This relay 104 is provided with an armature 105, which normally bears against a contact 130

point 106. Said armature is preferably grounded at 107, and the said contact point 106 can be connected by a conductor 108 with the supervisory lamp or clearing out signal 109. A conductor 110 preferably leads from said lamp or clearing out signal to an associated contact piece, and this single cord for the trunking operator is also preferably provided with a second clearing out signal or 5 supervisory lamp 111. The conductors 112 and 113 lead from this lamp 111, one leading to the battery and the other to a relay. The contact piece 114 is preferably connected with the said conductor 102, while the contact piece 115 is grounded. The contact piece 116 is connected with the conductor 110. The contact piece 117 is preferably connected to move the contact piece 115 when engaged by the armature 118 of the relay 119. 10 This relay is connected in parallel with the lamp 111, the coil of the relay and the lamp being preferably of equal resistance. The conductor 120 connects said relay with a battery, while the conductor 121 and the resistance 122 form medium of electrical connection between the contact piece 115 and the ground 123. The battery 124 is connected, as stated, with both the lamp 111 and the relay 119, and is preferably grounded at 15 25 30 35 40

This cord circuit thus provided serves as the connecting means by which the trunking operator is enabled to establish communication between the sub-station and the other exchange. It will be observed that this cord circuit consists of but a single cord—that is to say, there is but one plug, the other end of the cord circuit being connected directly to the conductors 126 and 127, constituting the complete metallic line connection between 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

At the second exchange, or at the exchange where the call is supposed to originate, the said trunk line terminals are connected with the tip and sleeve contacts 129 and 130 of an ordinary jack. At this second exchange the cord circuit is illustrated as of the usual form and character, and is such as is ordinarily employed in exchanges for connecting up two subscribers of the same exchange. This cord circuit for the originating operator is provided with a plug having tip and sleeve contacts 131 and 132, connected respectively with the tip and sleeve strands 133 and 134 of the said cord circuit. These strands lead preferably to the springs 135 and 136 of the ringing key. A conductor 137 and a ringing generator 138, grounded at 139 and connected by a conductor 140 with a contact point 141, are preferably associated with said ringing key. It will also be observed that contact points 142, 143 and 144 are provided, the latter being connected with the said conductor 137. The operator's listening circuit includes a conductor 145, a condenser 146, a contact point 147, a spring 148 of the listening key, and a conductor 149 connecting this spring with the contact point 142. The conductor 150 connects the other spring 151 of the listening key with the contact point 143. 70 The listening contact 152 and the conductor 153 are connected with the receiver of the operator's talking and listening set, and the condenser 146 is connected by the coil 154 and the conductor 155 with the said operator's receiver 156. The ground 157, together with the conductor 158 and the armature 159 are associated with the differential relay C. This armature is normally away from the relay, and is arranged to close a 80 supervisory lamp circuit by engaging the contact point 160. Said relay is provided with the differentially wound coils 161 and 163, the former connected with the spring 151 by a conductor 162. A like conductor 85 164 connects the relay coil 163 with the said spring 148 of the listening key. The supervisory lamp or clearing out signal 165 is interposed between the conductors 166 and 167, the latter being connected with the 90 relay contact point 160. The relay coil 163 is connected with a battery by a conductor 168, while the same battery is connected with the relay coil 161 by a conductor 169. The repeating coils 170 and 171 are arranged 95 at each side of said battery. The conductor 172 and the ground 173 are connected with the said battery, which is preferably composed of two separate batteries 174 and 175. This cord circuit is also provided with a second supervisory signal 176, it being observed that the system throughout is of the double supervisory character. This supervisory lamp 176 is connected by a conductor 177 with the battery 174. The said lamp is also 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955

have illustrated but one sub-station, and have shown only the switchboard apparatus for this station.

Thus it will be seen that as illustrated the system comprises the sub-station of a called subscriber, the switchboard apparatus at which the line of the sub-station terminates, the single cord and cord circuits of the trunking operator at the first exchange, and the cord circuit of the originating operator at the exchange where the call is assumed to have originated. As stated, the trunking cord circuit is shown connected with the originating operator's cord circuit by means of the conductor constituting what is commonly known as a "trunk line." As shown, the calling and the called subscribers are assumed to be connected and carrying on conversation. In such case, the relays 19 and 104 are energized, while the differential relays B, C and D, owing to their differential winding, allow the voice and talking currents to pass without being energized. It is the disconnecting apparatus and the circuit arrangement for the clearing out signals, to which my invention particularly relates, and assuming that the two subscribers are through talking, the operations are as follows: When the called subscriber hangs up the receiver 1, a grounded line circuit is immediately completed from the ground 4 through the bell 3 and the contact point 5 to the receiver hook or switch 2, thence through the line conductor 8 and the relay contact piece 13 to the adjacent contact piece 12, thence through conductor 30 to the tip contact 47, from the latter through the plug tip 50 and the cord strand 53 to the key spring 55, thence through the contact 56 and the conductor 61 to the key spring 65, through contact 67 and conductor 74 to key spring 76, thence through conductor 84 and relay coil 86 to conductor 97, through the latter and the repeating coil 96 to battery 95, and thence to ground at 98 and back to the ground connection at 4. The completion of this circuit serves to energize relay B, and to draw the armature 91 into contact with the contact point 88. The energizing of the differential relay B is, it will be seen, due to the fact that the returning of the receiver to the hook at the sub-station operates to open the sleeve side of the circuit, thereby cutting out the coil 87, and in this way permitting the coil 86, which is in the tip side of the circuit, to energize the relay. The energizing of this relay operates to close the local circuit from the ground 92 through the armature 91 to the contact 88, thence through the conductor 90 to the lamp 111, through the latter and the conductor 112 to the battery 124, thence to the ground at 125 and back to the ground at 92. The closing of this local circuit operates to light the said supervisory lamp 111, thereby advising the trunking operator that the called

for subscriber has hung up the receiver at the sub-station. With the relay 119 arranged in parallel with the said lamp 111, it will also be seen that a second local circuit is closed through the ground 92 and the armature 91 to the contact point 88, thence through conductors 90 and 113 to the relay 119, through the conductor 120 to the battery 124, and thence to the ground at 125 and back to the ground connection at 92. This shunting of the current serves to energize the relay 119, which immediately draws up its armature 118. The said armature in moving toward the core of the relay 119 engages the lower contact spring 117, and causes both the latter and the contact spring 115 to move upward and into engagement respectively with the contacts 116 and 114. The shifting of these contact pieces operates to close a grounded trunking line circuit from the ground 123 through the resistance 122 and the conductor 121 to the contact piece 115, thence through contact 114 and conductors 102 and 101 to the conductor 100, through the latter to the conductor 126 of the trunking line, through the tip contact 129 of the jack at the originating exchange, thence through the plug tip 131 and the cord strand 133 to the key spring 135, through contact point 143 and conductor 150 to conductor 162, thence through the coil 161 and the differential relay C, through conductor 169 and the repeating coil 170 to the battery 175, thence through conductor 172 to ground at 173, and back through ground to the ground connection at 123. The circuit thus established through the ground and part of the trunking line is energized by the battery 175, and as the coil 161 of the differential relay C is included in this circuit, it is therefore apparent that the latter will be energized and will attract its armature 159. This armature when attracted engages the contact point 160, thereby completing a local circuit from the ground 157 through the conductor 158 to the armature 159, thence through contact point 160 and conductor 167 to the supervisory lamp 165, through this lamp and the conductor 166 to the battery 175, thence through conductor 172 to the ground at 173, and thence back to the ground at 157. This, it will be seen, operates to light the lamp 165, so as to advise the originating operator at the exchange of the calling subscriber that the called for subscriber is through talking and has hung up the receiver. Thus it will be seen that the act of the called subscriber in hanging up the receiver operates to light both the lamps 111 and 165, and to consequently indicate to both the trunking operator and the originating operator that a disconnection may be made as soon as the calling subscriber is through and sends in a signal to that effect. The trunking operator, however, pays no attention to this signal, and

does not remove the plug of the trunking cord circuit from the jack until a disconnecting signal is received from the originating operator at the other exchange.

5 When the calling subscriber is through and hangs up the receiver, a grounded line circuit is completed through the supervisory lamp 176, and the originating operator seeing this signal understands that the subscriber 10 at the sub-station from whence the calling came is through and ready to be disconnected. The originating operator then withdraws the plug of the cord circuit from the jack having the tip and sleeve contacts 129 and 130, and this act on the part of the originating operator breaks or opens the energized circuit in which the relay 104 is included. This relay 104 is, it will be observed, energized while the subscribers are talking, 20 the source of current supply consisting of the battery 175 at the originating station. Consequently, as stated, when the originating operator withdraws the plug from the trunking line jack, this relay 104 is deenergized, 25 and its armature 105 is allowed to fall back into contact with the contact point 106. This operates to complete a local circuit from the ground 107 through the armature 105 and the contact point 106 to the conductor 108, thence through the supervisory lamp 109 and the conductor 110 to the contact point 116, through the contact spring 117 and the contact 128 to the battery 124, 30 thence to the ground at 125 and back to the ground connection 107. This, it will be seen, causes the current from battery 124 to light the supervisory lamp 109 through a short local circuit. This lamp when lighted indicates that the calling subscriber has signaled 35 for a disconnection, and that the originating operator has withdrawn the cord plug from the trunking line jack. The trunking operator acting on this signal from the originating operator, withdraws the plug of the 40 single trunking cord from the jack, having the tip and sleeve contacts 47 and 48, and in this way disconnects the called subscriber's line from the trunking cord circuit. Thus in disconnecting, the called subscriber can signal 45 both the trunking operator and the originating operator at the two exchanges, and the originating operator is permitted to completely supervise and control the disconnecting, and to indicate to the trunking operator 50 the time at which it is proper for the latter to make the final disconnection.

It will be seen that the cord circuit for the trunking operator, although consisting of but a single cord and plug, is advantageously 55 and desirably provided with two supervisory lamps. One of these lamps serves as a clearing out signal for a subscriber, while the other lamp serves as a clearing out signal for the operator at the other exchange. It will 60 be observed that both lamps are lighted by

comparatively short local circuits. It will also be observed that the local circuit for the lamp 109 is preferably provided with two switch points, one normally closed by the relay 104, and the other held normally open 70 by the relay 119. While the subscribers are talking, the normally closed switch point is held open by the relay 104, which latter is under the control of the originating operator at the other exchange. It is only when the 75 subscriber hangs up the receiver 1 that the relay 119 is operated, so as to close the normally open switch point. It will also be seen that this relay 119 is energized by and included in a comparatively short local circuit, 80 and that in this way there is no necessity of providing objectionable grounded circuits between the two exchanges for causing the operation of the lamp 109. This lamp is simply brought into operation by the breaking or opening of the trunk line circuit, so as 85 to release the relay armature 105. The arrangement also affords opportunity for an advantageous and effective use of a differential relay in a single cord trunk circuit. As a 90 further advantage, the circuit arrangement enables the originating operator to know when the called subscriber answers the call. In establishing connection between the two subscribers, the lamp 165 continues to glow 95 or burn until the called subscriber answers the call. It will be seen, therefore, that with the foregoing combination of relays and circuits, a complete and satisfactory supervision of the entire trunking system is 100 afforded both operators, and that at the same time the arrangement is simple and thoroughly efficient. Furthermore, no objectionable grounded or other circuit connections are employed, the certainty and efficiency 105 of the system being particularly insured by the local circuit arrangement for operating the supervisory lamps in the cord circuit of the trunking operator. In addition, the arrangement does not preclude the 110 use of a complete metallic talking circuit.

What I claim as my invention is:

1. In a telephone system, the combination of sub-stations, exchanges having suitable line connection with said sub-stations, a 115 trunk line between said exchanges, an operator's cord circuit at one exchange, a trunking operator's cord circuit at the other exchange, a supervisory signal associated with the said cord circuit of the trunking operator, a local circuit for operating said supervisory signal, a source of current supply included in said local circuit, a relay associated with said local circuit and adapted to hold the latter open while the subscribers are talking, a source of current supply 120 associated with said operator's cord circuit, and a trunk line circuit including said relay and said source of current supply, said trunk line circuit being broken and the said local 125 circuit being closed when the subscribers are talking.

65 130

- circuit being closed when the plug of the operator's cord circuit is disconnected from the trunk line, and the deenergization of said relay operating to close said local circuit and cause the operation of said supervisory signal.
2. In a trunking telephone system, the combination of a single cord and plug for the trunking operator, two supervisory lamps associated with said single cord, suitable local circuits and a source of current supply for operating said supervisory lamps, and a differential relay for controlling the flow of current through one lamp, and a plurality of relays for controlling the flow of current through the other lamp.
3. In a trunking telephone system, the combination of a single cord and plug for the trunking operator, a double cord for the originating operator, a trunk line between the two operators, a supervisory lamp associated with the said single cord, a source of current supply and a circuit for lighting said lamp, a relay and circuit for closing said lamp circuit at one point, a relay and a source of current supply and a suitable circuit for holding said lamp circuit open at another point while the subscribers are talking, the said lamp circuit being closed and the supervisory lamp lighted when the said double cord for the originating operator is disconnected from the trunk line.
4. In a trunking system, the combination of two sub-stations, two exchanges, complete metallic line connection between each exchange and its allotted sub-station, complete metallic line connection between said exchanges, a trunking operator's cord circuit at one exchange, an originating operator's cord circuit at the other exchange, a supervisory lamp associated with said trunking operator's cord circuit, a local circuit including said supervisory lamp, a relay adapted to be energized and to hold said local circuit open when the subscribers are talking, a source of current supply in the originating operator's cord circuit for energizing said relay, a second supervisory lamp associated with said trunking operator's cord circuit, a local circuit and a source of current supply for lighting said second supervisory lamp, and a differential relay for controlling the operation of said second supervisory lamp.
5. In a trunking telephone system, a trunking operator's cord circuit, a supervisory lamp associated with said cord circuit, a local circuit and a source of current supply for lighting said lamp, a shunt around said lamp, a relay located in said shunt, a second supervisory lamp and a local circuit for lighting the same, the local circuit of said second supervisory lamp being open at two points while the subscribers are talking, an armature and contact pieces for closing said local circuit at one point, said armature being associated with and operated by said relay, and a switch for automatically closing said local circuit at said other open point.
6. In a trunking telephone system, a trunking operator's cord circuit, a local circuit provided with two switch points, relays for closing said switch points, a supervisory lamp and a source of current supply included in said local circuit, a trunk line connected with one of said relays, and a sub-station line and a suitable relay for controlling the operation of the other of said relays.
7. In a trunking telephone system the combination of a single cord and plug for the trunking operator, a switchboard having jacks associated with said single cord, a sub-station having suitable line connection with said switchboard, a trunk line permanently connected with said single cord, two supervisory lamps associated with said single cord, local circuits and suitable sources of current supply for lighting said lamps, two relays for controlling two switch points in one of said local circuits, and a differentially wound relay for controlling a switch point in another of said local circuits.
8. In a trunking telephone system the combination of a trunking operator's cord circuit, a trunk line permanently connected with said trunking operator's cord circuit, an originating operator's cord circuit, a suitable plug and jack for establishing connection between said trunk line and said originating operator's cord circuit, supervisory lamps associated with said originating operator's cord circuit, local circuits and a suitable source of current supply for lighting said lamps, differentially wound relays for closing said local circuits, a switchboard associated with said trunking operator's cord circuit, a sub-station having suitable line connection with said switchboard, a switchboard associated with said originating operator's cord circuit, a sub-station having suitable line connection with said last mentioned switchboard, supervisory lamps associated with said trunking operator's cord circuit, a differential relay and a local circuit and a source of current supply for causing the lighting of one of said lamps in the trunking operator's cord circuit, and a pair of relays and a local circuit, together with a suitable source of current supply for controlling the lighting of the other of said supervisory lamps for the trunking operator.
9. In a telephone system the combination of sub-stations and a central station and line connection between the same, a cord circuit located at said central station, a supervisory lamp and a suitable source of current supply associated with said cord circuit, a shunt extending around said lamp, a relay in said shunt, and a signal circuit having a switch point controlled by said relay, together with a supervisory relay for controlling a normally

open switchpoint in the circuit of said lamp and relay.

10. In a telephone system, a cord circuit, a lamp signal associated with said cord circuit and adapted for indicating the condition of a line, a source of current supply, a local circuit including said lamp signal and source of current supply, a shunt around said lamp, a relay in said shunt, said relay having the same 10 resistance as said lamp signal, a supervisory lamp for indicating the condition of another line and a local circuit for operating the same, the local circuit for said supervisory lamp being provided with a switch point, and said relay being provided with an armature for 15 opening and closing said switch point.

11. In a telephone exchange system, the combination of a trunk line, a talking circuit including said trunk line, a differential relay 20 in the talking circuit, the windings of said relay neutralizing each other when thus connected in series, a suitable relay for controlling said differential relay over the trunk line, suitable circuit connections controlled 25 by said differential relay, and a third relay coöperating with said suitable relay to control the said differential relay.

12. In a telephone exchange system, the combination of a trunk line, a talking circuit 30 including said trunk line, a differential relay in the talking circuit, the windings of said relay neutralizing each other when thus connected in series, a suitable relay for controlling said differential relay over the trunk line, suitable circuit connections controlled 35 by said differential relay, a differentially wound electro-magnet having its neutralizing coils bridged in series across the talking

circuit, and means by which said electro-magnet coöperates with said suitable relay to 40 control said differential relay.

13. In a telephone exchange system, the combination of a trunk line, a talking circuit including said trunk line, a differential relay in the talking circuit, the windings of said relay neutralizing each other when thus connected in series, a suitable relay for controlling 45 said differential relay over the trunk line, suitable circuit connections controlled by said differential relay, and a third relay 50 coöperating with said suitable relay to control the said differential relay, and common batteries for feeding talking current through the differential coils to said circuit.

14. In a telephone exchange system, the combination of a trunk line, a talking circuit including said trunk line, a differential relay in the talking circuit, the windings of said relay neutralizing each other when thus connected in series, a suitable relay for controlling 60 said differential relay over the trunk line, suitable circuit connections controlled by said differential relay, a differentially wound electro-magnet having its neutralizing coils bridged in series across the talking circuit, and means by which said electro-magnet coöperates with said suitable relay to 65 control said differential relay, and common batteries for feeding talking current through the differential coils to said circuit. 70

Signed by me at Chicago, Cook county, Illinois, this 16th day of January, 1902.

ALFRED H. DYSON.
